STANDING TABLE FOR INVALIDS

Merle H. Charters, Paterson, N. J.

Application March 23, 1949, Serial No. 83,081

2 Claims. (Cl. 311—1)

1

This invention relates to an apparatus for the treatment of and the training of crippled persons. More particularly, the invention relates to a standing table, that is, a support providing means for holding the patient in upright, standing, position, the support providing a surface adjacent the person so held for supporting articles to be used by him.

The standing table of the invention is designed primarily for use with children who are victims of cerebral palsy, more commonly called "spastic paralysis." A person afflicted with this ailment has restricted control, in varying degrees, of the muscles of his body. Very frequently a child so afflicted cannot walk by himself and must be taught to do so by training him to correlate the muscles over which he has control. It is necessary, while training such person to stand and walk, to support him so that he cannot fall and injure himself, while still allowing him a certain degree of freedom of movement.

The standing table of the invention provides a recess or cut-out portion receiving the torso or trunk of the patient. The table is provided with a trunk embracing means secured to the table, such means giving the patient a firm bracing support while he is in the apparatus. In the preferred embodiment the standing table is so constructed as to give the patient freedom of movement about a vertical axis. Further, the table is preferably so constructed as to allow the adjustment of the distance from such trunk embracing means and consequently the patient to the inner edge of the cut-out portion in the table.

The table is further provided with a rest in the form of an elongated member spanning the rear edges of the arcuate cut-out portion of the table. When employed with the trunk embracing means such elongated spanning member is useful as an arm and elbow support for the patient. After the patient has improved so that he no longer requires the trunk embracing means, such means may be removed from the table, the patient being supported freely within the arcuate cut-out portion and the back engaging rest member spanning the rear corners of the cut-out portion.

It is accordingly an object of the invention to provide an improved standing table having means securely to hold the patient therein without injuring him.

It is a further object of the invention to provide a standing table of the type indicated having a trunk engaging means which provides freedom

of movement of the patient about a vertical axis within the cut-out portion of the table top. As indicated, in the preferred embodiment, the means for supporting the trunk embracing means is adjustable to vary the distance from the trunk engaging means or belt to the inner edge of the cut-out portion.

It is yet another object of the invention to provide a standing table which is convertible and adaptable, so that it is usable when the need for the trunk embracing means has passed, to support the patient with freedom of movement within the cut-out portion in the table top.

15 These and further objects of the invention will be more readily apparent upon consideration of the following description of a preferred embodiment of the standing table of the invention. In the drawing appended hereto which forms a part of such specification:

20 Fig. 1 is a view in perspective of the preferred embodiment of the standing table of the invention:

Fig. 2 is a fragmentary view in bottom plan of such standing table, the view being taken in the vicinity of the trunk embracing means and the supporting member therefor; and

Fig. 3 is a view in vertical section through the clamping and adjusting means for such trunk embracing means supporting member, the section being taken along the line 3—3 in Fig. 2.

30 In the illustrative embodiment of the standing table of the invention the reference character 2 designates the table top. The table top is supported in horizontal position by means of four telescopic legs of which the upper portions
35 attached to flanges on the underside of the table top are designated 4. The bottom ends of the legs 6, as indicated, telescope into sections 4, the table leg sections being held in the desired
40 adjusted position by means of the set screws shown at 8. As a result of such construction, the table is capable of use with patients of varying heights, the legs being adjusted so as to bring
45 the top of the table 2 to about the waist height of the patient.

40 of the patient. Table top 2 is provided, in the embodiment shown, with a circular arcuate recess or cut-out portion 10 located centrally of one long edge thereof. Bridging the outer, rear corners of recess 10 is the elongated back rest 12 which is held in position by means of the bolts 14 extending through the depending leg of L-shaped brackets screwed to the bottom of the table top, as shown in Fig. 2. Bolts 12 extend through vertical slots 50 at the ends of member 12, member 12 being held

in place by the tightening up of the wing nuts 16 on the bolts 14. It is apparent that member 12 may readily be removed by loosening nuts 16 and lifting it vertically off the bolts 14.

Within the recess 10 and positioned approximately on a level with the table top is the trunk embracing means generally designated by the character 18. The forward portion of means 18 is composed of a broad strip of metal bent generally into U-shape, such strip being shown at 20. To the bottom forward edge of member 20 at its central portion there is riveted the vertical ear of L-shaped bracket 28 which forms a part of the means by which element 18 is attached to the table top. Member 20 of the trunk engaging means is provided with a lining member 22 in the form of a broad strap of padded cloth or the like, such member continuing past the rear edges of member 20 to form a belt, part 24 thereof which engages the back of the patient being adjustably engageable with a buckle 26 attached to the other end of the lining member.

Bracket 28, as explained, is of L-shape, the vertical leg thereof being riveted to member 20 at the bottom edge of the latter so as to hold the member 18 upwardly within the recess 10. The other, horizontal, leg of member 28 is pivotally attached by pin 32 to the forward end of the longitudinally extending supporting member 30, as shown in Fig. 2. The forward end of member 30 runs within the U-shaped guiding clip 34 which is attached, as shown, to the underside of the table top. The rear end of member 30 is bifurcated, as shown, the two parallel arms at such rear end being designated 36. Projecting downwardly from the underside of the table top is the vertical stud 38 which is affixed to the table top in the manner shown in Fig. 3. The two arms 36 of member 30 lie on either side of stud 38 and may travel longitudinally relative thereto.

Mounted on stud 38 is a locking shoe shown at 40, the stud 38 extending through a central vertically disposed hole in the locking shoe. The bottom surfaces of legs 36 are serrated, as shown in Fig. 2. The confronting, top surface of the locking shoe 40 is correspondingly serrated, so that when such shoe is pressed into engagement with arms 36 it holds them securely against longitudinal motion. Shoe 40 is prevented from rotary movement by means of the upwardly projecting ear 49 which extends between the two arms 36.

The locking shoe is advanced into locking engagement with arms 36 and is maintained in such relationship by means of a nut on the bottom end of stud 36, such nut being in the form of an operating knob 44. It will be apparent that member 30 is confined to straight line movement by reason of its being guided by the clip 34 and the stud 38. When it is desired to adjust member 30 and, consequently, trunk engaging or embracing means 18 with respect to the inner edge of recess 10, it is necessary only to loosen knob 44 to slide member 30 to the desired longitudinal position, and again to tighten nut 44. The pivotal mounting at 32 between trunk embracing means 18 and the forward end of member 30 allows a patient mounted within member 18 a substantial degree of freedom of movement about the vertical axis defined by pin 32, as indicated by the dashed lines in Fig. 2.

In Fig. 2 the back rest 12 is omitted from the table. In some instances such back rest is not necessary and its omission allows the person held within means 18 more freedom of pivotal movement than he would have if it were present. Back

rest 12, however, may be used to advantage in combination with means 18, particularly when means 30 is adjusted to bring the trunk embracing belt 18 close to the rear edge of the recess 10. 5 When belt 18 is in such adjusted position and the back rest 12 is in place, the latter member functions advantageously as a support for the hands and forearms or elbows of the patient.

The table shown is further of advantage when the patient has progressed in his muscular training to a point at which the trunk embracing means 18 is no longer necessary. When such point in the training is reached, the back rest 12 is removed, the clamping means 40 is loosened by 10 loosening nut 44, after which belt 18 and its supporting member 30 may readily be withdrawn from the table. The patient may then be supported within the recess 10 of the table, the back rest 12 being applied thereto. The patient then 15 has freedom of movement within the recess 10 while still being supported by the table and the back rest.

The table of the invention, therefore, is distinguished by its ready adjustability and its 20 ready adaptability, being useful for children from tender years until they reach adolescence or beyond. Such adjustments are effected by adjustment of the legs, by adjustment of the size of belt 18, member 20 being readily deformed to 25 fit various trunk sizes, and eventually by the ready removal of means 18 and its support 30 after which, as above indicated, the table may be employed simply with the back rest 12 to restrain the patient and to maintain him within 30 the recess 10.

Although for purposes of illustration I have 35 described and illustrated a preferred embodiment of the standing table of my invention, it will be apparent that the invention is not confined, in its broader aspects, to such embodiment, since 40 it is capable of considerable variation as to details. The invention is, therefore, defined by the scope of the claims appended hereto.

I claim as new the following:

1. A standing table for invalids comprising a 45 broad surfaced table top, means to support the table top in elevated horizontal position generally at the waist height of a patient, said table top having a substantially circularly arcuate recess in one edge thereof, said recess being substantially larger than the trunk of the patient, a rigid elongated supporting member, means rigidly to secure said supporting member to the table top parallel to the table top and with the inner end of such supporting member projecting radially into the recess at approximately the midpoint of such recess, a broad belt means at said recess to embrace the trunk of the patient standing with his torso in the recess, the forward portion of such belt means being substantially rigid, and vertical pivot means attaching the forward portion of the belt means which confronts the edge of the recess at approximately its lateral center to the inner end of the supporting member so that the belt means may move in a horizontal plane about the pivot means.

2. A standing table for invalids comprising a 50 broad surfaced table top, means to support the table top in elevated horizontal position generally at the waist height of a patient, said table top having a substantially circularly arcuate recess in one edge thereof, said recess being substantially larger than the trunk of the patient, a rigid elongated supporting member, means attaching 55 said supporting member to the table top parallel

to the table top and with the inner end of such supporting member projecting radially into the recess at approximately the midpoint of such recess, said last named means comprising means guiding the supporting member for reciprocation radially of the recess in the table top and means to clamp the supporting member in adjusted position on the table top, a broad belt means at said recess to embrace the trunk of the patient standing with his torso in the recess, the forward portion of such belt means being substantially rigid, and vertical pivot means attaching the forward portion of the belt means which confronts the edge of the recess at approximately its lateral center to the inner end of the supporting member so that the belt means may be moved in a horizontal plane about the pivot means.
